UNITED STATES PATENT OFFICE.

JAMES H. RAND, OF NEWTON, MASSACHUSETTS.

INDEX.

1,278,213.

Specification of Letters Patent. Patented Sept. 10, 1918.

Application filed October 11, 1917. Serial No. 196,028.

To all whom it may concern:

Be it known that I, JAMES H. RAND, a citizen of the United States, and resident of Newton, in the county of Middlesex, and 5 State of Massachusetts, have invented new and useful Improvements in Indexes, of which the following is a specification.

This invention relates to card indexes of the overlapping card, visible index type and 10 consists in the improvements hereinafter described and particularly pointed out in the claims.

In the accompanying drawings, which illustrate an embodiment of the invention,— 15 Figure 1 is a front elevation of part of an index containing the invention;

Fig. 2 is a similar view showing some of the index elements swung upward on their hinges;

20 Fig. 3 is a front elevation of one of the index elements;

Fig. 4 is a section, on an enlarged scale, on line 4—4 of Fig. 1;

25 Fig. 5 is a section on line 5—5 of Fig. 2; and

Fig. 6 is a front elevation of part of an index element showing a modification.

A represents the frame or panel in which the overlapping index elements are mounted. 30 The frame is preferably made of sheet metal and is provided at its opposite edges with inturned flanges *a* which form inwardly facing guide channels to receive the ends of rails or bars to which the index elements 35 are hinged.

B is a bar or rail which is preferably made of bristol board, or some other material sufficiently resilient to permit it to be bent at the middle part away from the frame for the 40 purpose of drawing the ends toward each other to insert them into or remove them from the guide channels. A hanger C of wire or other suitable flexible or resilient material extends lengthwise of the rail B, 45 and is secured thereto at its ends. The preferred method of attaching the wire hanger to the rail is to bend over its ends, pass them through perforations in the rail, and clench or upset them on the rear side of the rail 50 as shown at *c*. The ends of the hanger terminate short of the flanges *a* so as not to extend into the guide channels.

A card or sheet D is supported and hinged

on each hanger by means of a lip *d*, which preferably is made of a strip of sheet celluloid, or some sheet material sufficiently stiff to hold its shape but at the same time sufficiently flexible or resilient to bend with the rail B. The lip *d* may be folded over the edge of the sheet D and attached to the margin thereof on the rear side leaving the front flap free so that the hanger C may be inserted under the lip. It is desirable to leave enough space between the fold of the lip *d* and the edge of the card D to receive the hanger C so that the hanger C will be in the same plane with the card when the parts are assembled, instead of being offset therefrom either to the front or rear. The ends of lip *d* terminate short of the ends of the hanger thereby permitting the card D to be shifted somewhat lengthwise of the hanger and so displaced laterally of the frame and the series of cards. Normally the flanges *a*, will engage the edges of the cards D and so hold them in central position in the frame, but by springing one end of the card over the adjacent flange *a* the card may be displaced and project from the series as shown in one instance in Fig. 1, and so constitute a signal to guide the user to a particular card should he wish for any reason to refer to it readily without looking through the series to find it.

Many of the advantages of the invention may be obtained with the features thus far described, and the cards D themselves may be used for receiving the desired entries or records. The card D, however, is preferably used as a holder to support another removable card or sheet insert E, which overlies the card holder D and is attached thereto by slipping its upper edge under the lip *d* and its lower edge under another lip, *d'* at the opposite edge of the card holder. The lip *d'* is preferably made of transparent sheet material, such as celluloid, and is of sufficient depth to form a protective sheath for the margin of the card E which is exposed to view when the cards are arranged as shown in overlapped relation. Any index titles or other inscriptions on the lower exposed margins of the cards will show through the transparent protective sheaths or lip *d'*, but will be protected thereby from wear or soiling. The lips *d* are folded

around the lower edges of the cards D and secured to the margins on the back side, while the front flap is free to form a trough or pocket to receive the edge of the insert E.

In the modification shown in Fig. 6 two short hangers C' are used in place of a single longer hanger, and two lips d' engage the hangers instead of a single lip as in the other form. The ends of the lips d' may terminate short of the ends of the hangers C', as in the other case, to permit the card to be displaced lengthwise of the rail B as already explained; and in other respects the structure may be the same as in the other form.

The rails B are removable from the frame, interchangeable with one another, and slidable lengthwise of the frame in the 20 guide channels. The cards D are removable from their supporting rails and are interchangeable; and the card inserts E are also removable and interchangeable. The folded strip of celluloid or the like, d, has sufficient resilience to cause the lip d to engage the face of the card D with a light elastic pressure, so that after it is sprung open to allow the hanger C to enter the fold, it will again close against the card, thereby 30 holding the hanger in place and preventing the card from dropping off or becoming dislodged when it is swung upward, as shown in the upper parts of Figs. 2 and 5. The resilient lip d also serves yieldingly to grip 35 the margin of the card insert E and to aid in holding it in position.

In use any of the cards may be swung upwardly on their hinge connections, as illustrated in Figs. 2 and 5, to expose the body 40 of any desired card for the purpose of inspecting it or making entries on it; and if the user desires to return to any card in the series for any purpose it may be shifted or displaced sidewise of the frame as shown in Fig. 1, to serve as a signal to guide him to 45 the card in question. A further advantage of the invention is that by mounting the frame on a stand or support in a slightly inclined position as illustrated in Fig. 5. The 50 upwardly swung cards will of themselves remain in upstanding position as shown without having to be held by the operator. This is due in part to the fact that the hinge connection, formed by the fold of lip d and the hanger C, which is positioned beyond 55 the edges of the card, lies in the plane of the card, so that when the cards are swung upward even a little past the vertical, the center of gravity is behind the hinge and 60 the cards tend to remain in upstanding position; and in part to the fact that the rail and hanger, being of flexible resilient material, tend normally to curve or bulge forwardly very slightly from the face of the 65 frame, and so act with a gentle spring pres-

sure to hold the cards in either extreme position up or down, the curve or bulge being flattened as the cards swing past their median position.

I claim:

1. An index comprising a frame, a series of supports mounted on the frame, a series of cards held by the supports in overlapped spaced relation, and means for attaching the several cards to their respective supports 75 adapted to permit any card in the series to be individually displaced laterally with relation to the series, without removing it from the frame or detaching it from its support.

2. An index comprising a frame, a series of supports mounted on the frame, a series of cards adapted to be attached to the supports in overlapped spaced relation, and hinge connections between the several cards 85 and their supports adapted to permit any card in the series to be individually displaced laterally with relation to the series without removing it from its support.

3. An index comprising a frame having 90 inwardly facing guide channels, a series of supporting rails having their ends mounted in said guide channels, a series of cards adapted to be attached to the supporting rails in overlapped spaced relation, and hinge connections between the several cards and their supporting rails adapted to permit any card 95 in the series to be individually displaced laterally with relation to the series without removing it from its support.

4. An index comprising a frame having inwardly facing guide channels, a series of supports each comprising a rail having its ends mounted in the guide channels and a hanger extending lengthwise of and attached at its ends to the rail, constituting 105 one hinge member, and a series of cards having a hinge member engaging the hanger and adapted to slide lengthwise thereof, whereby any card in the series may be displaced laterally with relation to the series 110 without removing it from its support.

5. An index comprising a frame having inwardly facing guide channels, a series of supports each comprising a rail having its 115 ends mounted in the guide channels and a hanger extending lengthwise of and attached at its ends to the rail, constituting one hinge member, and a series of cards having a folded over member engaging the hanger 120 and forming the other hinge member, said folded over hinge member terminating short of the ends of the hanger, whereby any card in the series may be displaced laterally with 125 relation to the series without removing it from its support.

6. An index comprising a frame having inwardly facing guide channels, a series of supports each comprising a rail having its ends mounted in the guide channels and a 130

- hanger extending lengthwise of and attached at its ends to the rail, constituting one hinge member and a series of cards having a folded over lip, free at one edge, constituting the other hinge member, said lip terminating short of the ends of the hanger, whereby any card in the series may be displaced laterally with relation to the series without removing it from its support. 5
- 10 7. An index comprising a frame, a series of supports each including a lengthwise extending hinge member, and a series of cards each having a hinge member engaging the hinge member of the support and adapted to position the latter beyond the edge of the card and in the same plane with the card. 15
8. An index comprising a frame having inwardly facing guide channels, a series of supports each including a rail having its ends mounted in the guide channels, and a wire hanger extending lengthwise of and attached at its ends to the rail, and a series of cards each having a hinge member engaging the wire hanger adapted to position the latter beyond the edge of the card and in the same plane with the card. 20
9. An index comprising a frame having inwardly facing guide channels, a series of supports each including a rail having its ends mounted in the guide channels, and a wire hanger extending lengthwise of and attached at its ends to the rail, and a series of cards each having a lip folded over the 25 edge of the card, the fold being spaced from the edge, engaging the wire hanger and adapted to position the latter beyond the edge of the card and in the same plane with the card. 30
- 40 10. An index element comprising a rail having a lengthwise extending hanger secured at its ends to the side of the rail, and a card having a hinge connection to the hanger adapted to be displaced lengthwise 45 of the hanger. 11. An index element comprising a rail having a lengthwise extending hanger secured at its ends to the side of the rail, and a card having a strip of sheet material secured to one edge of the card and folded over the edge of the card, the fold of said strip constituting a hinge member engaging the hanger. 50
- 55 12. An index element comprising a rail having a lengthwise extending hanger secured at its ends to the side of the rail, and a card having a strip of sheet material one edge of which is secured to one margin of
- the card and the other edge of which is free and is folded over to engage the hanger. 60
13. An index element comprising a rail having a lengthwise extending hanger secured at its ends to the side of the rail, and a card having a strip of sheet material one edge of which is secured to one margin 65 of the card and the other edge of which is free and is folded over upon the opposite face of the card constituting a lip to engage the hanger. 14. An index element comprising a rail 70 having a lengthwise extending hanger secured at its ends to the side of the rail, and a card having a strip of resilient sheet material one edge of which is secured to one margin of 75 the card, and the other edge of which is free and is folded over upon the opposite face of the card and bears against the latter face of the card with a yielding pressure. 15. An index element comprising a rail 80 having a lengthwise extending hanger secured at its ends to the side of the rail, and a card having a strip of sheet material one edge of which is secured to one margin 85 of the card and the other edge of which is free and is folded over to engage the hanger, and a card insert mounted on the first named card one edge of which is retained in position by the free edge of the folded hinge strip. 90
16. An index element comprising a rail having a lengthwise extending hanger secured at its ends to the side of the rail, and a card having a strip of resilient sheet material one edge of which is secured to one margin 95 of the card, and the other edge of which is free and is folded over upon the opposite face of the card and bears against the latter face of the card with a yielding pressure, and a card insert mounted on the 100 first named card one edge of which is gripped by the resilient free edge of the folded hinge strip. 17. An index element comprising a wire hanger and a card having a strip of resilient sheet material one edge of which is secured to one margin of the card and the other edge of which is free and is folded over the edge of the card to engage the hanger, said free folded edge being adapted to yield 110 to admit the hanger, and to close to prevent the accidental dislodgment of the hanger from the fold when the parts are assembled. Signed by me at Boston, Massachusetts, this 8th day of October, 1917.

JAMES H. RAND.
